HOUSING FOR A HEART MONITOR

Gilbert G. Pfaff, Holland, and Harry J. Edenhofer,
Southampton, Pa., assignors to Princo Instruments, Inc., Southampton, Pa., a corporation of Pennsylvania

Filed Nov. 21, 1968, Ser. No. 14,575

Term of patent 14 years

Int. Cl. D24—02; D14—02
U.S. Cl. D83—1

Fig. 1

Fig. 2

Fig. 4

Fig. 3

FIGURE 1 is a perspective view of a housing for a heart monitor showing my new design;

FIGURE 2 is a perspective view of the housing in an alternate position;

FIGURE 3 is a plan view as seen from the top of FIGURE 1; and

FIGURE 4 is an elevation as seen from the right of FIGURE 3.

The undisclosed portion as seen from the rear of FIGURE 1 is plane and unornamented.

The dominant features of my design reside in the portions shown in full lines.

We claim:

The ornamental design of a housing for a heart monitor, as shown and described.
